UNITED STATES PATENT OFFICE.

JAMES H. FLETCHER, OF NEWARK, NEW JERSEY.

SEWING-MACHINE.

SPECIFICATION forming part of Letters Patent No. 443,756, dated December 30, 1890.

Application filed February 16, 1884. Serial No. 121,004. (Model.)

To all whom it may concern:

Be it known that I, JAMES H. FLETCHER, a citizen of the United States, residing in the city of Newark, county of Essex, and State of New Jersey, have invented new and useful Improvements in Sewing-Machines, of which the following is a specification.

My invention consists in certain improvements in sewing-machines whereby the feed and tension may be simultaneously regulated, in a manner and for the purpose as will hereinafter be set forth.

Referring to the drawings, Figure 1 represents a side view of a sewing-machine containing my improvement, partly in section, the latter being shown by broken lines; Fig. 2, end view, partly in section, showing feed and lever for changing throw of feed; Fig. 3, thread-tension device in section, together with line of connection to rock-shaft; Fig. 4, side view, partly in section, disclosing to view lever-connections; Fig. 5, broken detail, showing end of rock-shaft and arm. Fig. 6 represents a vertical sectional view of a section of driving-shaft, can, eccentric-strap, connecting-rod, and crank-pin. Fig. 7 represents a longitudinal sectional view through the bed-plate and mechanism supported beneath the same, band-wheel, &c., shown in Fig. 1.

The form and style of machine to which I have applied my improvements is that known as the "Willcox & Gibbs," although it is obvious that it is equally applicable to other styles.

In the drawings, A represents the cloth-plate of the sewing-machine. B is the arm of the same.

C is the driving-shaft, provided at its rear end with a cam or eccentric located thereon. (More clearly shown in Figs. 3 and 6.)

D is the feeding device.

F is a rock-shaft arranged parallel with the driving-shaft beneath the cloth-plate of the machine, and is provided at its front end with an arm F', having a pin or other projection supporting a roller f thereon, which engages on slides within a slot or opening in one side of a connecting-rod E at one end thereof. (More clearly shown in Fig. 4.) The said connecting-rod E at its opposite end is pivotally connected to the feeding device at d and

serves to vary the throw of the feed-dog, and thereby the length of stitch, as will be more fully explained hereinafter.

55

E' is a stitch-regulating cam-lever, pivotally secured to the frame beneath the cloth-plate of the machine, as shown in Figs. 2 and 4, provided with a pin or other projection supporting a roller thereon adapted to slide 60 or operate within a slot or opening located in the said connecting-rod E on the side opposite the slot or opening before referred to therein. (See Fig. 4.)

Referring to Fig. 2, it will be readily observed that by shifting the handle of the stitch-regulating cam-lever E up or down it changes the position of the roller f in the groove on the opposite side of the lever E, thereby making a greater or less throw to the 70 feed when the rock-shaft F and eccentric-strap J are operated by the cam C' on the driving-shaft.

G is a reciprocating vertically-operating connecting-rod operated by the said cam or eccentric C', located on the said driving-shaft C, which serves to automatically raise the upper part or plate of the thread-tension device, represented at H, as will be hereinafter described. The said rock-shaft F is provided 80 at its rear end, or that end adjacent to the band-wheel, with an arm F, having a slot or groove therein. (More clearly shown in dotted lines in Fig. 3.) The connecting-rod is provided with an eccentric-strap J, located 85

within an opening in the lower extremity of said connecting-rod and provided with a crank-pin f', having a roller thereon (see Fig. 6) adapted to operate in the slot or opening in the arm located at the end of the rock-shaft 90 F. (See Fig. 3.) One side of the end of the said vertical connecting-rod G is cut away (see Figs. 3 and 6) to allow a slight vibration and adjustment of said eccentric-strap.

The cam or eccentric on the driving-shaft operates or 95 revolves within an opening in the said eccentric-strap, which operates the vertical connecting-rod G and gives the same an up-and-down motion, and at the same time oscillates the rock-shaft through the medium of the eccentric-strap J and crank-pin on said eccentric-strap operating in the slot in the fixed arm on said rock-shaft.

The tension device proper (represented at

H in Fig. 3 of the drawings) consists of the lower fixed plate and the upper plate, the latter adapted to be raised and lowered with the action of the vertical connecting-rod G. Between said plates or surfaces the upper thread from the spool is passed to the needle.

The operation of my improved device is as follows: The thread from the spool is passed between the two impinging plates of tension device II toward the needle-bar and downward to and through the needle-eye in the usual manner. Uniformity of pressure upon threads of varied sizes is secured by means of the continuous connection of the several parts hereinbefore described. By moving the cam-lever E' for determining the length of stitch, the connecting-rod E is moved, thereby varying the length of stitch or throw of the feed-dog, and at the same time moving the rock-shaft F by reason of its crank-pin connection with the said connecting-rod E. (See Fig. 4.) The said movement or adjustment of the rock-shaft by the cam-lever E', as described, alters the position of the slotted arm located on the opposite end of said shaft, which in turn moves the eccentric-strap which forms the bearing for the vertical connecting-rod G, thereby adjusting the position and movement of the same. The movement or adjustment of the eccentric-strap as described varies the space between the plates forming the tension device, and when the desired adjustment is made for the length of stitch usual for a certain size or number of thread the tension is determined simultaneously with it, and any change of stitch changes the tension device at the same time. The rock-shaft is operated by the action of the crank-pin f' on the eccentric-strap within the groove or

opening in the fixed arm of said rock-shaft. When said eccentric-strap is operated by the cam C' on the driving-shaft and at the movement or adjustment of the rock-shaft by the cam-lever E', as described, the position of the fixed arm at its end is varied, thereby moving the eccentric-strap in which the cam on the driving-shaft operates, which movement or change of position also varies the throw of the vertical rod G.

I claim—

1. The combination, in a sewing-machine, of the feeding device, a main driving-shaft provided with a cam or eccentric thereon, a rock-shaft and an eccentric-strap connecting said cam or eccentric and rock-shaft, a rod connecting said rock-shaft and feeding device, a feed-adjusting cam or lever, a thread-tension device, and a rod connecting said tension device and said eccentric-strap, substantially as described, and for the purpose set forth.

2. The combination, in a sewing-machine, of the feeding device, a main driving-shaft provided with a cam or eccentric thereon, a rock-shaft and an eccentric-strap connecting said cam or eccentric and rock-shaft, a rod or lever connecting said rock-shaft and feeding device, a thread-tension device, a rod connecting said tension device and said eccentric-strap, and means for adjusting the throw of said rock-shaft, whereby said feeding device and tension device are adjusted simultaneously, substantially as described, and for the purpose set forth.

JAMES H. FLETCHER.
